[57] CLAIM

The ornamental design for a sound insulating cover for
card punching machine or the like, as shown and de-
scribed.

DESCRIPTION

FIG. 1 is a top front perspective view of a sound insulat-
ing cover for a card punching machine showing the
new design of the present invention; and

FIG. 2 is a bottom rear perspective view thereof.
The wood grain is partially shown for convenience of
illustration, it being understood that the wood grain is
continuous over the cover.
